ROTATABLE SIGN, OR SIMILAR ARTICLE

Clark L. Lofgren, Golden Valley, Minn., assignor to The Cornelius Company, Anoka, Minn., a corporation of Minnesota

Filed Dec. 12, 1968, Ser. No. 14,939

Term of patent 14 years

Int. Cl. D20—03

U.S. Cl. D96—12

FIG. 1 is a side elevational view of a rotatable sign or similar article showing my new design, the opposite side of the upper rotatable portion being the same as the side shown, and the opposite side of the base being a mirror image of the side shown.

FIG. 2 is a right end elevational view thereof.

FIG. 3 is a top plan view thereof.

FIG. 4 is a cross-sectional view taken along line IV-IV of FIG. 1.

I claim:

The ornamental design for a rotatable sign, or similar article, substantially as shown and described.
